UNITED STATES PATENT OFFICE.

JOSEPH J. DILLON, OF WILMETTE, ILLINOIS.

PULLEY.

1,224,152.

Specification of Letters Patent.

Patented May 1, 1917.

Application filed December 21, 1916. Serial No. 138,213.

To all whom it may concern:

Be it known that I, JOSEPH J. DILLON, a citizen of the United States, residing at Wilmette, in the county of Cook and State 5 of Illinois, have invented new and useful Improvements in Pulleys, of which the following is a specification.

This invention relates to pulleys for sash cords, and its object is to provide a novel 10 and improved support and casing for said pulley so constructed and arranged that it guides the cord to prevent the same from slipping off the pulley.

The invention also has for its object to 15 provide a pulley casing which affords complete protection to the pulley and that portion of the cord which runs over the pulley, and also to provide a casing which is in sections to enable the pulley to be readily inserted in place therein, together with a 20 novel and improved means for holding the casing sections assembled in a manner precluding all danger of the sections getting out of alignment.

25 The objects stated are attained by means of a combination and arrangement of parts to be hereinafter described and claimed, and in order that the same may be better understood, reference is had to the accompanying 30 drawing forming a part of this specification.

In the drawing,

Figure 1 is a vertical section showing the application of the invention, and

35 Fig. 2 is a perspective view of the pulley casing.

Referring specifically to the drawing, 5 denotes a grooved pulley over which the sash cord 6 is trained, said cord being attached at one end to the sash 7 and having connected at its other end the weight 8. The pulley is housed in a casing having spaced opposite side walls 9 carrying the shaft 10 on which the pulley is journaled. The casing 40 has a curved top 11 to conform to the curvature of the pulley periphery. The side walls 9 are flat and they are connected at their ends by end walls 12. The casing is closed at the bottom by a wall 13 provided 45 with openings through which the sash cord 6 passes, these openings being lined with bushings 14. The bushings are metal tubes, which, when they are inserted in the openings are of greater length than said openings 50 so that they project at both ends. The projecting ends of the tube are then rolled 55

outward to grip or clench opposite sides of the wall 13, and to leave the ends of the tube rounded and perfectly smooth, thereby reducing wear of the sash cord to a mini- 60 mum.

In order to facilitate the insertion of the pulley 5 into the casing, the latter is divided transversely into two sections, one of which carries the pulley shaft 10, the dividing line or joint between the sections being shown at 15. At the dividing line, one of the sections has an outstanding flange 16 which projects from the sides and also from the top and the bottom thereof. The other 70 section has a similar flange 17, and when the sections are assembled, the two flanges come together in face-to-face relation and by screws or other suitable fasteners 18 passed through the top and bottom projecting portions of the flanges, the two sections of the casing are fastened together. The flange 16 is larger than the flange 17 and has a recess 19 in its face in which the latter flange seats. The upper and lower ends of 75 the recess are tapered or V-shaped and the corresponding ends of the flange 17 are correspondingly shaped to fit snugly therein, whereby perpendicular and sidewise slippage of the two casing sections relative to 80 each other is effectually prevented, and they are securely held assembled. This is desirable as one of the openings for the sash cord 85 is in one of the casing sections and the other opening is in the other section. The 90 openings are therefore kept in perfect alignment to properly guide the sash cord and prevent it from slipping off the pulley 5.

The device is mounted in a recess 20 in the window frame 21 in such a position 95 that one end of the casing projects over into the groove 22 of the sash rail in which the sash cord end to which the sash 7 is attached runs, the opening in the casing through which the sash cord passes being in 100 line with this groove. The other end of the casing projects over into that part of the window frame in which the weight 8 travels. The casing is held in place by the screws 18 which are long enough to pass into the 105 window frame also.

By the structure hereinbefore described the sash cord 6 is effectually prevented from jumping off the pulley 5 and it is held closely, yet smoothly, to the pulley. No dust 110 or water can enter the pulley casing and the cord is therefore completely protected.

The device also permits the use of a rope, cable, or chain instead of the common sash cord. Referring to Fig. 1 of the drawing, it will be seen that the device is supported at three points, the top and the bottom of the recess forming two supports, and that portion of the window frame 21 against which the flange 16 abuts forming the third support. The first two supports guard against sudden vertical thrusts of the sash, and the third against lateral tug of the sash cord, and other dislodging tendencies.

I claim:—

15 The combination of a sash cord pulley, and a guide for the sash cord, said guide comprising a casing inclosing the pulley and divided transversely and off its center into two sections, the meeting ends of the

sections having outstanding abutting flanges, 20 the flange of one section having a recess in its face in which recess the flange of the other section seats, the ends of the recess being reduced in width and the ends of the last-mentioned flange being shaped to fit in 25 said reduced ends of the recess, and fastening means passing through the flanges of the casing sections, each of said sections comprising a bottom, a top, side walls and an end wall, the larger section supporting 30 the pulley and its bottom having a guide opening for one end of the sash cord, and the bottom of the smaller section being provided with a guide opening for the other end of the sash cord.

35 In testimony whereof I affix my signature.

JOSEPH J. DILLON.
